DUMPING GRATE MECHANISM

Anthony M. Meyerstein, Nutley, N. J., assignor of three-fourths to Rosoff Bros., Inc., Brooklyn, N. Y., a corporation of New York, and one-fourth to Anthony M. Meyerstein, Inc., New York, N. Y., a corporation of New York

Application August 26, 1936, Serial No. 97,877

8 Claims. (Cl. 126—169)

This invention relates to an improved dumping grate mechanism such as may be used, for example, in connection with garbage and refuse incinerators.

5 Dumping grates for incinerators and other types of furnaces have heretofore been supported in closed position by means of toggle members. But such prior arrangements have not been entirely satisfactory because of incorrect design 10 and improper location of the necessary counterweights and for other reasons. The counterweights have been associated with the toggle members in such a manner that the opening of the grates has caused the counterweights to strike the adjacent furnace walls thereby injuring the same. Furthermore the counterweights have not been positioned properly with respect to the center of mass of the associated dumping grates. Accordingly, considerable effort has been necessary to move the grates between closed and open 15 positions.

It is the object of the present invention so to design the dumping grate supporting mechanism and associated counterweights that the grates 20 will be more securely held in ash-supporting position and more easily dumped by the furnace operator without the possibility of the counterweights striking and injuring the furnace walls. In the present arrangement each counterweight 25 is at maximum displacement from the shaft upon which the grate is supported when the grate is fully opened, or dumped. Thus the counterweight can immediately give maximum assistance as soon as the grates are moved toward 30 closed position. When the grates are in the latter position the counterweights lie close to the grate shaft and have the minimum tendency to resist movement of the grates as the latter are moved toward open position. Thus the grates 35 are dumped more quickly and the furnace, or incinerator, may be operated with greater speed than has been possible heretofore.

Another object is to provide stop means for 40 limiting the positions of the dumping grates both in their closed and opened positions and to provide safety devices for holding the grates in these 45 positions.

A further object is to arrange the grate mechanism in such a manner that no dead plates are necessary and the maximum area between division walls of the furnace may be used for grate 50 surface.

Further objects of the invention will be apparent from the following description, taken in

conjunction with the accompanying drawings, in which

Fig. 1 is a front elevation of a furnace embodying a preferred arrangement of the present invention;

Fig. 2 is a partial sectional view taken substantially along the line 2—2 of Fig. 3;

Fig. 3 is a partial sectional view taken substantially along the line 3—3 of Fig. 2 and showing the grates in closed position;

Fig. 4 is a similar view showing the grates dumped, or in open position.

Referring to the drawings, and more particularly to Figs. 2—4, the numeral 1 indicates the division walls of the furnace upon which the grate mechanism is supported by means of a frame 2 resting upon the walls as shown. Stationary grates 3 are supported upon the frame 2 along the edges adjacent the furnace walls 1. It will be observed that these grates extend from the dumping grates to the division walls 1 and that the entire area between these walls is used for grate surface. The movable, or dumping, grates 4 are rotatably supported upon the shaft 5 which extends across the grate opening and has its ends supported in the bushings 6, as shown more clearly in Fig. 2. These bushings are supported in the depending flanges 7.

The supporting shaft 5 passes through bearings 8, the upper halves of which are formed integral with the under surfaces of the dumping grates, while the lower halves are integral with the arms 9 to which the upper ends of the counterweights 10 are secured.

As shown in Fig. 2, the upper portions of the counterweights 10 are bifurcated to accommodate the toggle members hereinafter described. The counterweights are suspended from the rods 11 which are supported in the lower ends of the arms 9.

The operating shaft 12 is rotatably supported in the bearings 13 and passes through the hangers 14 which are supported by the flanges 7. On either side of the counterweights 10 guide links 15 are supported upon the operating shaft 12 and are connected to the lower portion of the counterweights by means of the pins 16 projecting into the counterweights. While the operating shaft 12 has been shown as being located directly below the shaft 5, upon which the dumping grates are supported, this arrangement is not essential and shaft 12 may be located either to the left or right of a vertical line through the axis of shaft 5.

From this description it will be apparent that

when the dumping grates are closed, as shown in Fig. 3, the counterweights are close to vertical lines passing through the axes of the supporting shafts 5. When the dumping grates are moved 5 to open positions, as shown in Fig. 4, the counterweights are moved away from these vertical lines by the downward movement of the grates. When the grates have been fully opened by rotation of the operating shaft as hereinafter described, the 10 counterweights 10 have been raised to their highest positions and are displaced their maximum distance from these vertical lines. When the operating shaft 12 is rotated in the opposite direction to close the grates, the counterweights afford the greatest assistance in the upward movements of the grates. Since the upper and lower portions of the counterweights are secured by the arms 9 and guide links 15, respectively, there is no possibility of the counterweights striking 15 and thereby injuring the furnace walls 1. The counterweight guide links 15 may be connected 20 by means of the bars 17 which assure uniform movement of each of the counterweights and further prevent any possible swaying of the counterweights while the dumping grates are being 25 opened and closed. It is important that the counterweights should not strike the furnace walls 1 because such walls are usually constructed of masonry which may be injured thereby to such 30 an extent that in time they will lack the necessary strength to support the grates.

The dumping grates are supported in closed position and are dumped by means of a toggle mechanism comprising the cranks, 18, secured to 35 the operating shaft 12, and the links 19 connected to the dumping grates. The upper ends of the links 19 are adjustably connected to the depending bosses 20 on the under sides of the dumping grates by the threaded members 21 40 which permit adjustment of the effective lengths of the toggle members. Bosses 22 projecting from the undersides of the grates are provided with adjustable studs 23 which abut against the projections 24 near the upper ends of the toggle 45 links 19. When the grates are fully closed, as shown in Fig. 3, the arms 18 and links 19 are slightly out of alignment. The projection 24 contacting the adjusting screws 23 limit the closing movements of the toggle members. The dumping 50 grates are thus held in closed positions until the cranks 18 are rotated so as to "break" the toggle linkages. As shown in Fig. 4, the projections 24 on the toggle links 19 abut against the cranks 18 and thereby limit the opening positions 55 of the dumping grates.

When it is desired to dump the grates, the arms 18 are rotated by the operating shaft 12. This movement "breaks" the toggle connection to the grates and permits the grates to fall, due to their 60 own weight plus the weight of the material supported thereon. Operating handles 25 are attached to the ends of the shafts 12 and are provided with latches 26 adapted to hold the handles in the position shown in Fig. 1 when not being used, thereby acting as safety devices to hold the dumping grates in closed positions if the toggle links should break. Each of the handles is provided with a depending arm 27 having a hole 28 therein. When the handles have been 65 moved so as to open the grates fully these holes are in alignment with the holes 29 in the channel member 30. Bolts may be inserted in these holes to hold the grates fully opened, if desired.

As shown in Fig. 2 the toggle cranks 18 are 70 located in the spaces between the bifurcated up-

per portions of the counterweights which enables the toggle links 19 to be connected to the middle portions of the grates and thereby reduce the possibility of the counterweights swaying during opening and closing of the grates. 5

I claim:

1. In dumping grate mechanism, a supporting shaft for the grate, an operating shaft, toggle members connected to the grate and actuated by said operating shaft, a counterweight, and 10 a member connected thereto and rigidly to the grate and rotatable about said supporting shaft.

2. In dumping grate mechanism, a supporting shaft for the grate, an operating shaft, toggle members connected to the grate and actuated by 15 said operating shaft, a counterweight rotatably connected to a member which is rigidly fastened to the grate and rotatable about said supporting shaft, and adjustable stop members for limiting the position of the toggle arms when the grate 20 is in closed position.

3. In dumping grate mechanism, a supporting shaft for the grate, an operating shaft, toggle members connected to the grate and actuated by 25 said operating shaft, a counterweight, a member connecting a part of said counterweight with said supporting shaft, a second member connecting another part of said counterweight with said operating shaft, said members raising the counterweight to its maximum height and lateral displacement from said shafts when the grate is 30 fully dumped.

4. In dumping grate mechanism, a supporting shaft for the grate, an operating shaft, said shafts being in substantially vertical alignment, toggle 35 members connected to the grate and actuated by said operating shaft, a counterweight, a member connected to said counterweight, rigidly connected to the grate and rotatable about said supporting shaft, said member being adapted to raise said counterweight to its maximum height and lateral displacement when the grate is 40 fully dumped.

5. In dumping grate mechanism, a supporting shaft for the grate, an operating shaft, said 45 shafts being in substantially vertical alignment, toggle members connected to the grate and actuated by said operating shaft, a counterweight, members connected to the upper and lower portions of said counterweight, the upper-connecting 50 member being rotatable about the grate-supporting shaft and the lower-connecting member being rotatable about the operating shaft, said members being adapted to raise said counterweight to its maximum height and lateral displacement 55 from said shafts when the grate is fully dumped, and adjustable stop members for limiting the position of the toggle arms when the grate is in closed position.

6. In dumping grate mechanism, a supporting 60 shaft for the grate, an operating shaft, toggle members adapted to break downwardly when the grate is dumped comprising a link connected to the grate and a crankarm connected to said link and rotated by said operating shaft to break the toggle, a counterweight and members connected 65 to said counterweight at spaced points thereon and rotatable about said shafts.

7. In dumping grate mechanism, a supporting shaft for the grate, an operating shaft, toggle members adapted to break downwardly when the 70 grate is dumped comprising a link adjustably connected to the grate so that its effective length may be varied and a crankarm connected to said link and rotated by said operating shaft to break 75

the toggle, adjustable stop means between said link and grate to limit the closing position of the toggle members, a counterweight, and links connected at spaced points thereon and rotatable about said shafts to place said counterweight at its maximum height and lateral displacement from said shafts when the grate is fully dumped.

5. 8. In dumping grate mechanism, a supporting shaft for the grate, an operating shaft, toggle

members including a link connected to the grate and having a projection thereon and an arm actuated by said operating shaft, said grate having a stop member abutting against said link to limit the upward breaking movement of said toggle members and said projection contacting said arm to limit the open position of the toggle members.

5

ANTHONY M. MEYERSTEIN.
